UNITED STATES PATENT OFFICE.

GOODWIN B. SMITH, OF PHILADELPHIA, PENNSYLVANIA.

RUFFLE WAIST.

1,118,313.

Specification of Letters Patent. Patented Nov. 24, 1914.

Application filed June 16, 1911. Serial No. 633,470.

To all whom it may concern:

Be it known that I, GOODWIN B. SMITH, a citizen of the United States, residing at Philadelphia, in the county of Philadelphia and State of Pennsylvania, have invented certain new and useful Improvements in Ruffle Waists, of which the following is a specification.

This invention relates to wearing apparel for women, and particularly to ruffle waists and similar articles employed to improve the appearance of the figure.

It is well known that waist extending ruffles and similar devices have generally been unsatisfactory, owing to the fact that the ruffles or flounces become flattened or matted, which is caused by wear.

It is an object of this invention to provide a ruffle to overcome the above referred to difficulty, by constructing said ruffle so that the same may be readily laundried.

An important object of this invention is to provide a ruffle made of suitable fabric and provided with a section of stiffening material attached to the same and extending longitudinally thereof to hold the ruffle in the most distended position when gathered, together with novel means for attaching the ruffle to the waist and causing the same to be gathered.

A further object of this invention is to provide a ruffle waist of the above character, which is simple in construction, cheap to manufacture, cool, light, and easy to launder.

A further object of the invention is to provide a ruffle waist, wherein means are provided to vary the gathered state of the ruffle, so that different degrees of fullness will be afforded by the garment to suit the particular wearer.

A further object of the invention is to provide in a ruffle waist of the above character, means whereby the ruffle will hold its shape when gathered for a long time and is not liable to be flattened or distorted.

The invention is carried out by providing a body or corset waist to which are attached adjustable ruffles, having draw-strings running longitudinally therethrough. By proper manipulation of the draw-strings the ruffles may be gathered and hence made to give any desired degree of fullness. Each of the ruffles is free from attachment to the waist, at least, at one end, whereby the same may

be distended to lie flat, for the purpose of laundrying.

In the accompanying drawings forming a part of this specification and in which like numerals are employed to designate like parts throughout the same, Figure 1 is a perspective view of my improved garment, Fig. 2 is a sectional view taken on line 2-2 of Fig. 4, Fig. 3 is a similar view taken on line 3-3 of Fig. 4, Fig. 4 is an outer side view of the body or waist, showing one ruffle crimped and the other distended to lie flat, Fig. 5 is a sectional view taken on line 5-5 of Fig. 4, Fig. 6 is a similar view taken on line 6-6 of Fig. 4, Fig. 7 is a similar view taken on line 7-7 of Fig. 4, Fig. 8 is a similar view taken on line 8-8 of Fig. 4, and, Fig. 9 is a detail view showing a slightly different manner of securing the ruffle to the waist.

In the drawings wherein is illustrated a preferred embodiment of my invention, the numeral 1 designates as a whole, a body or waist formed of a plurality of sections 2, 3 and 4, which are preferably formed of a washable fabric. These sections are suitably shaped, as shown, so when they are stitched together, as shown at 5, the waist will fit the wearer. At the lower end of the sections 2, 3 and 4 is attached a ruffle 6, and this union is reinforced by a tape 7, stitched as shown at 8, (see Fig. 3) to said sections and ruffle. This tape affords a casing for the reception of a draw or tie string 9. The body or waist is preferably formed open in the back and the string 9 is adapted to extend around the waist of the wearer to hold the garment in proper place. One section 2 is provided with a button 10 and the other section 2 with a loop 11 for detachable engagement therewith. A tape 12 is folded about the edges of the body or waist 1 and is stitched thereto, as shown. Openings 13 are provided to receive the arms of the wearer. Upper portions of the sections 2 and 3 are reduced to form straps 14 and 15, respectively, which are adapted to be detachably connected through the medium of a safety pin 16 or other suitable device. The body or waist may preferably be trimmed with lace 17, extending about the tape 12, as shown.

Disposed upon one side of the body or waist, preferably the outer side thereof, is a pair of ruffles 18, each of which has one

end only stitched or attached to the body 1 adjacent the arm opening 13. Each of these ruffles 18 is provided along its two longitudinal edges with hems 19, stitched, as shown at 20. The ruffle is also provided at its free end with a transverse hem 21, stitched, as shown at 22. Within the two hems 19 extend draw-strings 23 operating between the two rows of stitching 20, as 10 more clearly shown in Fig. 2. Corresponding ends of the draw-strings 23 are attached to the body or waist 1, adjacent the arm-holes 13. Each of the ruffles 18 is provided preferably upon its outer side with a strip 15 of summer netting or other stiffening fabric 24, which is disposed longitudinally of the ruffle midway of its longitudinal edges. The strip 24 is stitched or otherwise attached to the ruffle.

20 As shown in Fig. 9, the ruffle 18 is not stitched or attached to the waist but is only connected therewith through the draw-strings 23, which are attached to said waist in the same manner as hereinabove described. By this construction the ruffle 18 may be distended to lie flat for the purpose of ironing or may be entirely removed from the waist. This arrangement also makes it possible to regulate the fullness under the 30 arm.

As illustrated in Fig. 1, the body or waist 1 is in the position that it occupies when being worn. The ruffles 18 are gathered and the free ends of the draw-strings 23 of one 35 ruffle are tied to corresponding draw-strings of the other ruffle. The ruffles 18 may be more or less gathered to give the desired degree of fullness. The section of stiffening material 24 aids in holding the ruffle in its 40 requisite shape when gathered. As clearly shown in Fig. 4, one of the ruffles 18 is shown distended or stretched out so that the same will lie perfectly flat. This is done when the garment is being laundered and 45 particularly during the ironing process. It will thus be seen that the ruffles are easily ironed, which is an important feature of the invention. When the ruffle is not stitched to the waist, as shown in Fig. 9, the 50 same may be removed from said waist, as hereinabove stated.

I wish it understood that the form of my invention herewith shown and described is to be taken as a preferred example of the 55 same and that certain changes in the shape, size and arrangement of parts may be resorted to without departing from the spirit of the invention or the scope of the subjoined claims.

60 Having thus described my invention, I claim:—

1. The combination with a body or waist, of oppositely arranged pairs of draw-strings having their outer ends permanently 65 attached to the body or waist adjacent the

arm holes thereof and their inner adjacent ends free from permanent connection with the waist, a ruffle to be mounted upon each pair of draw-strings, said ruffle being formed of a single section of fabric having 70 longitudinal pockets formed adjacent the longitudinal edges thereof to receive the draw-strings in the pair, the ruffle being normally perfectly flat both longitudinally and transversely and being free from 75 flounces and lateral extensions upon its surface, whereby the ruffle may be readily ironed in its flat condition, said ruffle being free from connection with the material of the body or waist and longitudinally bodily 80 movable upon the draw-strings both when in its crimped condition and distended position, whereby the crimped ruffle may be bodily shifted to fill out the exact desired portion of the body and may be readily 85 bodily removed from the body or waist for the purpose of ironing or substitution.

2. The combination with a body garment adapted to conform generally to the bust of the wearer, of a pair of approximately 90 horizontal transversely crimped outwardly bulging bust producing ruffles arranged upon the body garment in proximity to the bust of the wearer, and means connecting the ruffles with the body garment so that 95 the inner ends of the ruffles are permanently free to be moved toward and away from each other to increase or decrease the degree of transverse crimping of the ruffles.

3. The combination with a body garment 100 adapted to conform generally to the bust of the wearer, of a pair of approximately horizontal strings arranged upon one side of the front of the body garment with their outer ends secured to the garment, and a pair of 105 approximately horizontal bust producing ruffles separate from the garment and provided with longitudinal hems to receive the strings, whereby the ruffles when transversely crimped and arranged upon the pair of 110 strings may be bodily moved longitudinally thereof toward and away from each other.

4. The combination with a body garment adapted to conform generally to the shape of the bust, of a plurality of approximately 115 horizontal strings arranged upon one side of the front of the body and secured thereto, and an approximately horizontal ruffle adapted to be transversely crimped and provided near its longitudinal edges with 120 means to receive the strings and adapted to be longitudinally distended by movement of portions thereof longitudinally of the strings until the same lies flat thereon.

5. The combination with a body garment 125 adapted to conform generally to the shape of the bust, of a plurality of strings secured near their outer ends to the body and adapted to be approximately horizontally arranged upon one side of the front of the 130

body, a ruffle adapted to be transversely crimped and provided with spaced longitudinally extending means to receive the strings, and a longitudinal strip of stiffening material secured to the ruffles between the string receiving means and possessing a substantially higher degree of stiffness than the material of the ruffle.

6. The combination with a body garment 10 adapted to conform generally to the shape of the bust, of a plurality of pairs of approximately horizontal strings arranged upon one side of the body garment with their outer ends attached to the body garment adjacent the arm holes thereof and

their inner ends permanently free from connection with the body garment and adapted to be detachably tied together, and approximately horizontal bust producing ruffles adapted to be transversely crimped, said 20 ruffles being provided with longitudinal hems to receive the strings and adapted to be longitudinally shifted upon the strings and removed therefrom when desired.

In testimony whereof I affix my signature 25 in presence of two witnesses.

GOODWIN B. SMITH.
